DESIGN FOR A PERFUME CONTAINING BROOCH

Rudolph Dopyera, Los Angeles, Calif.

Application May 18, 1940, Serial No. 92,448

Term of patent 7 years

To all whom it may concern:

Be it known that I, Rudolph Dopyera, a citizen of the Republic of Czechoslovakia, residing at Los Angeles, in the county of Los Angeles and State of California, have invented a new, original, and ornamental Design for a Perfume Containing Brooch, of which the following is a specification, reference being had to the accompanying drawing, forming a part thereof.

In the accompanying drawing, Fig. 1 is a side elevational view of the perfume containing brooch showing my new design;

Fig. 2 is an end view of the device shown in Fig. 1; and

Fig. 3 is a top plan view of the device shown in Fig. 1 partly in section and with the bail swung to one side and the stopper removed.

I claim:

The ornamental design for a perfume containing brooch, as shown.

RUDOLPH DOPYERA.
